LOCKING DEVICE FOR GATES

Grover M. Black and Carroll N. Bell, Dayton, Ohio

Application January 5, 1954, Serial No. 402,234

2 Claims. (Cl. 292—76)

This invention relates to improved locking mechanism for gates especially but not exclusively for lawn or fence gates, which have latching structure involving a flexible detent and a fixed or rigid keeper engaged thereby, and more particularly to a novel attachment adapted to be secured to the support carrying the latching structure detent and arranged to be engaged with the detent so as to prevent flexing of the detent to a released position and to be disengaged with the detent to permit normal flexing of the detent to a released position, relative to the keeper of the latching structure.

The primary object of the invention is to provide an efficient, practical, and easily installed device of the character indicated above which will, when in operative position, preclude opening of a closed gate by young children and animals.

Another important object of the invention is to provide a simple and rugged device of the character indicated above which can be made in an attractive and serviceable form at a low enough cost to insure widespread distribution and use thereof.

Other important objects and advantageous features of the invention will be apparent from the following description and the accompanying drawings, wherein, for purposes of illustration rather than limitation, a specific embodiment of the invention is set forth in detail.

In the drawings:

Figure 1 is a fragmentary and contracted side elevation showing a conventional fence mounted gate having locking means equipped with a device in accordance with the present invention;

Figure 2 is an enlarged fragmentary elevational detail, partly in vertical longitudinal section and partly broken away, showing the device in operative retaining relation to the flexible detent of the gate locking mechanism;

Figure 3 is a horizontal section taken on the line 3—3 of Figure 2;

Figure 4 is a view substantially similar to Figure 2 but showing the device in inoperative relation to the detent;

Figure 5 is a transverse vertical section taken on the line 5—5 of Figure 4.

Figure 6 is a view similar to a portion of Figure 2, but showing a padlock securely engaged with the device and the detent;

Figure 7 is a transverse vertical section taken on the line 7—7 of Figure 6; and

Figure 8 is a fragmentary transverse vertical section showing an alternative form of clamping means.

Referring in detail to the drawings, wherein like numerals designate like parts throughout the several views, the numeral 9 generally designates a conventional form of swing gate positioned between longitudinally spaced vertical posts 10 and 11 of a fence or the like. The post 11 can be a building or other support.

The gate 9 includes a frame involving vertical side or end members 12 and 13, the member 12 being hingedly supported on the fence post 10 by conventional hinge

2

means 14. On the gate frame member 13 is mounted a conventional flexible detent 15 which is engageable, in the closed position of the gate 9, with a conventional fixed keeper 16 which is mounted on the fence post 11.

5 The detent 15 comprises a vertically elongated flexible arm 17 which is fixedly secured at its lower end to the gate side member 13, as indicated at 18, and carries on its upper end a flexible U-shaped clip or yoke 19. The flexible arm 17 inclines away from the gate side member 13 10 and the yoke or clip 19 extends toward and embraces the gate side member 13.

The yoke or clip 19 includes a bight portion 20 and arms 21, 21 which have at their free ends laterally inwardly curved abutment portions 22, 22 terminating in outwardly turned terminals 23, 23. The terminals 23, 23 facilitate spreading of the arms 21, 21 in applying the yoke or clip 19 to the gate side member 13, and the abutment portions 22, 22 normally engage the laterally inward side of the member 13 and opposite the laterally outward tensioning of the detent 15.

The keeper 16 may comprise an angle iron form having a curved vertical arcuate flange 24 fitting the fence post 11 and a horizontal flange 25 projecting from the post 11 toward the gate 9. A curved securing flange 26

25 engages the opposite side of the post 11 from the flange 24 and is secured to the opposite ends of the flange 24

by means of bolts 27, 27. The horizontal flange 25, as shown in Figure 3, has a generally arcuate free edge 28 which is provided intermediate its ends with a detent receiving notch 29 of slightly greater width than the bight portion 20 of the yoke or clip 19. The gate 9 is maintained in the closed position by engagement of the bight portion 20 of the yoke 19 in the notch 29, in a well known manner, and opening of the gate 9 in either

30 direction is accomplished simply by pushing the gate 9 in the desired direction so that the detent yoke 19 is cammed out of the notch, against the tension of the detent arm 17, by the related one of the cam noses 30, 30

35 provided at the opposite sides of the notch 29. The detent 19 can also be disengaged by hand from the notch 29.

In accordance with the present invention, the above described gate latching mechanism is supplemented by a lock, generally designated 32, which comprises a relatively rigid, vertically elongated bar 33 having on its upper and lower ends right angular upper and lower ears

34 and 35, respectively, the upper ear 34 serving as a handle and stop and the lower ear 35 serving as a locking plate.

50 The middle of the bar 33 may be offset toward the side of the ears 34 and 35, as indicated at 36, to provide clearance with an element 37 on the gate side member 13, if desired. The bar 33 has upper and lower vertically elongated slots 38 and 39, respectively, which are located

55 above and below the offset part 36.

Extending through the lower slot 39 and threaded into a hole 40 previously provided in the gate side member 13 is a self-threading bolt or screw 41 having the shank

42 and the head 43. Circumposed on the shank 42 and compressed between the head 43 and the adjacent side of the bar 33 are washers 44 and 45, and a compressible

60 spacer 46, of rubber or the equivalent, the last being under sufficient compression to cause strong frictional engagement of the washer 44 with the bar 33, which holds

55 the lock 32 against vagrant vertical shifting of the lock 32 from a manually selected position relative to the gate side member 13.

65 The lock 32 is mounted by the bolt 41 on the gate side member 13 in such a position that when the lock 32 is in a depressed position with the bolt 41 engaged with the upper end of the lower slot 39, the locking plate 35 will

be positioned between the arms 21, 21 of the yoke 19, intermediate the upper and lower edges of the arms 21, 21, as shown in Figures 1, 2, 5, 6 and 7. As seen in Figures 2 and 3, the locking plate 35 is of such length that its preferably squared free end 47 is then close to the bight portion 20 of the clip or yoke 19. As a result, both flexing of the yoke 19 toward the gate side member 13 and out of the notch 29 and sidewise or rotative movement of the yoke 19 relative to the member 13 are precluded, and operation of the gate latching mechanism is precluded.

A self-threading lock clamping bolt 48 extends through the upper slot 38 of the lock 32 and is threaded in a hole 49 previously provided in the gate side member 13. The bolt 48 includes a shank 50 having a threaded outer end 51 upon which is threaded a wing nut 52. In the lock clamping position the wing nut 52 bears against the adjacent side of the bar 33, the nut 52 being adapted to be tightened by hand, to a degree sufficient to preclude its being loosened by small children, so that the lock 32 will be retained against being elevated out of locking position by small children, but can be loosened by persons having sufficient strength.

The locking plate 35 is preferably provided with a central hole 53 for accommodating, as shown in Figures 6 and 7, the hasp 54 of a padlock 55, the hasp 54 being wide enough to embrace an arm 21 of the yoke 19 while passing through the locking plate hole 53, whereby the lock 32 is positively locked in its depressed detent locking position.

In an alternate arrangement, shown in Figure 8 of the drawings, a self threading bolt 48' consists of a threaded shank 50' threaded in a hole 49' in the gate side member 13, and the shank 50' is integral with the wing nut 52', instead of having the wing nut threaded on the shank.

What is claimed is:

1. A latch for a swinging gate adapted to be mounted on the free side member of the gate opposite a notched keeper member adapted to be mounted on a stationary gate support adjacent to which the free side member is located in the closed position of the gate, said latch comprising a vertical bar extending lengthwise of said free side member, means mounting said vertical bar on said free side member and acting to confine said bar to end-

wise adjustment along said free side member and against rotation thereon, said bar having a lateral locking plate on one end thereof, a resilient yoke mounted on said free side member at said one end of the vertical bar and engageable in the notch of the keeper member in the closed position of the gate, said yoke having a U-shaped portion, including spaced arms located at opposite sides of said free side member and a bight portion, said vertical bar being movable along said free side member from an inactive position to a locking position in which said locking plate is engaged between said arms and between the free side member and the bight portion on said yoke.

2. A latch for a swinging gate adapted to be mounted on the free side member of the gate opposite a notched keeper member adapted to be mounted on a stationary gate support adjacent to which the free side member is located in the closed position of the gate, said latch comprising a vertical bar extending lengthwise of said free side member, means mounting said vertical bar on said free side member and acting to confine said bar to end-wise adjustment along said free side member and against rotation thereon, said bar having a lateral locking plate on one end thereof, a resilient yoke mounted on said free side member at said one end of the vertical bar and engageable in the notch of the keeper member in the closed position of the gate, said yoke having a U-shaped portion, including spaced arms located at opposite sides of said free side member and a bight portion, said vertical bar being movable along said free side member from an inactive position to a locking position in which said locking plate is engaged between said arms and between the free side member and the bight portion on said yoke.

15 5 10 15 20 25 30 35

2. A latch for a swinging gate adapted to be mounted on the free side member of the gate opposite a notched keeper member adapted to be mounted on a stationary gate support adjacent to which the free side member is located in the closed position of the gate, said latch comprising a vertical bar extending lengthwise of said free side member, means mounting said vertical bar on said free side member and acting to confine said bar to end-wise adjustment along said free side member and against rotation thereon, said bar having a lateral locking plate on one end thereof, a resilient yoke mounted on said free side member at said one end of the vertical bar and engageable in the notch of the keeper member in the closed position of the gate, said yoke having a U-shaped portion, including spaced arms located at opposite sides of said free side member and a bight portion, said vertical bar being movable along said free side member from an inactive position to a locking position in which said locking plate is engaged between said arms and between the free side member and the bight portion on said yoke, and means mounted on said free side member and acting on said vertical bar for releasably locking said vertical bar in either its inactive or its locking position.
